UNITED STATES PATENT OFFICE.

FRANK KAHLER, OF DILLON, MONTANA.

GATE-OPERATING MECHANISM.

1,424,913.

Specification of Letters Patent. Patented Aug. 8, 1922.

Application filed November 30, 1920. Serial No. 427,408.

To all whom it may concern:

Be it known that I, FRANK KAHLER, a citizen of the United States of America, and resident of Dillon, in the county of Beaverhead and State of Montana, have invented 5 certain new and useful Improvements in Gate-Operating Mechanism, of which the following is a specification.

This invention relates to gate constructions and more particularly to novel means 10 for operating the gate at a point remote from the supporting posts thereof, thus eliminating the necessity of a person alighting from a vehicle to accomplish the opening 15 and closing of the gate.

The primary object of the invention is to provide a mechanical means constructed to raise the gate to a predetermined position 20 from where the gate automatically moves to its open or closed position under its weight.

A further object of the invention is to provide means to permit the gate to drop to a cam way when in its open position to accomplish the automatic closing of the gate. 25 A still further object of the invention is to provide means for cushioning the downward movement of the gate, thus relieving the gate of the strain usually directed thereto when the same is moving to its closed 30 position.

With the foregoing and other objects in view, the invention consists in the details of construction and in the arrangement and combination of parts to be hereinafter more 35 fully set forth and claimed.

In describing the invention in detail, reference will be had to the accompanying drawings forming part of this specification wherein like characters denote correspond- 40 ing parts in the several views in which—

Figure 1 is a perspective view of the gate showing the location of the gate with relation to a roadway;

Figure 2 illustrates a longitudinal sec- 45 tional view through the post socket constructed in accordance with the present invention;

Figure 3 illustrates a plan view of the socket, the supporting gate post being 50 shown in section;

Figure 4 illustrates a transverse sectional view through the socket, the same being taken on line 4—4 of Figure 2;

Figure 5 illustrates a sectional view taken 55 on line 5—5 of Figure 3;

Figure 6 is a fragmental view of the supporting post of the gate;

Figure 7 is a fragmental view disclosing the upper end of the socket member;

Figure 8 illustrates a longitudinal sec- 60 tional view through the socket member, the supporting post of the gate being shown as positioned therein;

Figure 9 illustrates a sectional view taken 65 on the line 9—9 of Figure 8;

Fig. 10 illustrates a perspective view of one of the releasing rods; and

Fig. 11 illustrates a perspective view of one of the sliding bars.

My invention embodies certain improve- 70 ments in operating mechanism for gates of that type which are opened and closed from a distance by manually operated means which function to lift the gate when it is closed, such lifting positioning a supporting 75 stud on the stile of the gate upon an inclined surface whereby the gate will gravitate to an open position in which it is held until other manually operated means are actuated which allows the stud to contact 80 with another inclined surface to close the gate and to hold it in such position. Instead of the manually operated means referred to, such means may be mechanically operated, especially if it is desired to apply 85 the gate to a railway crossing, or to some other place requiring an automatic gate.

In these drawings the reference character 5 designates the socket member of the gate operating means which is embedded in the 90 ground's surface, the upper edge thereof lying in a plane in spaced relation with the ground's surface in which the socket member is positioned.

This socket member is provided with a 95 central bore 6 extending from the upper end thereof to a point in spaced relation with the bottom thereof to provide a seat for the lower end of the coiled spring 7, the upper end of which has engagement with the lower end of the gate stile or supporting post 8, which is of a diameter slightly less than the size of the bore 6 in which the same is supported, so that the stile may be free to turn within the bore.

The upper extremity of the bore 6 is cut away as at 9 to provide a clearance for the pin 10 carried by the supporting post 8 and in this cut away portion 9 are positioned 100 the ribs 11 and 12, the upper surfaces 13 of 110

which are inclined in opposite directions, and the under surfaces thereof being similarly but reversely inclined. The adjacent ends of the ribs 11 and 12 are supported in spaced relation with each other to provide a passageway 14, which passageway forms a continuation of the recessed portion 15 formed in the socket member and in which recessed portion is normally positioned the 5 pin 10 for supporting the gate 4 in closed position. The opposite ends of the ribs 11 and 12 are disposed in spaced relation with the shoulders 16, also formed in the socket member, which shoulders 16 form abutments 10 for the pin 10 to restrict movement of the post 8 in its movement to an open or closed position.

Openings 17 extend through the socket member and as shown these openings include 20 enlarged portions 18 adapted to house the coiled springs 19 which, in turn, embrace portions of the releasing rods 37' positioned in the openings 17, the inner ends of the rods 37' extending into suitable openings 25 provided in the ribs 11 and 12 for closing the space between the ends of the ribs 11 and 12 and the shoulders 16, for purposes to be hereinafter more fully described.

Associated with the socket member 5 is a 30 stationary post 21 which has its lower end anchored in the socket member, the upper end thereof terminating at a point an appreciable distance from the upper end of the socket member 5 for supporting the gate proper to insure the efficient operation thereof. A cross arm 22 has connection with the upper end of this post 21, and as shown the arm 22 supports the pulleys 23 and 24 over which operates the flexible connecting member 25 that has one of its ends secured to the supporting post 8, the opposite end thereof having connection with the counterbalancing weight 26. A collar 27 has connection with the post 21 at a point substantially intermediate the length thereof, and encircles the supporting post 8.

Extending inwardly from the collar 27 are the pins 28, which pins are disposed on opposite sides of the collar and cooperate 50 with the camming blocks 29 secured to opposite sides of the supporting post 8 for causing the gate proper to move away from the post 21 when the same is lifted to accomplish the operation of closing or opening 55 the same. The gate proper is of the usual construction, the outer end of which contacts with the post 30 to restrict movement thereof, the post 30 being provided with any conventional form of keeper to secure the gate 60 in its closed position.

As shown in Figs. 1 and 8, ropes, cables or other flexible operating members 31 and 32 are connected to the top of the gate supporting post 8 at 33', and thence pass upwardly 65 to guide pulleys 33 and 34' on the cross arm

22, and after passing over these pulleys, said members extend in opposite directions from the gate to posts 34 positioned on opposite sides of the gate at points remote therefrom. At the top of the posts 34 are 70 guide pulleys 37' over which the operating members 31 and 32 pass and then extend downwardly to within easy reach of the operator. To the members 31 and 32 are also connected branches 31' and 32' which extend downwardly and are connected to the sliding bars 35.

The sliding bars 35 are provided for retracting the rods 37' which block the passage of the stud or pin 10 to the lower incline. 80 The bars 35 are slidably mounted in openings in the base 5. Each bar 35 has a camming surface 36' which operates in a slot 37 in an intermediate enlarged portion of the rod 37'. Around the rear end 35' of each rod 37' is coiled a spring 19 for holding the rod normally advanced in blocking position. Each bar 35 has a laterally projecting pin 38' which extends into a recess 39' in the base 5, to limit the movement of said bar. 90

In the operation of the device, assuming that the gate is in its closed position or in a position as indicated by Fig. 1 of the drawing, one of the flexible members is operated, with the result that the gate is lifted. When 95 the gate reaches a predetermined height, the same is swung laterally on its pivot, which movement is caused by the pin 10 of the gate moving over the inclined upper surface of either of the members 11 or 12. In this position, the gate is resting on one of the pins 37' and is in an open position.

To close the gate, the opposite flexible member is operated to operate the bar 35 to 105 retract the pin 37' permitting the pin 10 to drop down between one of the ribs and the shoulder 16 formed in the socket member whereupon the gate gravitates over the inclined surface formed at the bottom of the cut away portion in the upper end of the socket member 5, the pin dropping into the recessed portion 15. While I have described the operating means on one side of the gate, it is to be understood that this structure is duplicated on the opposite side of the 110 gate to accomplish the operation of the gate upon the opposite side.

It might be further stated that openings 38 are provided in the base of the socket member 5 which openings provide means of 120 communication between the bore 6 and the ground surface in which the socket member is positioned to permit the water or dampness which might collect in the bore to pass outwardly therefrom.

From the foregoing description taken in connection with the drawings it will be noted, that the supporting base for the gate post or stile has two inclined ways, a vertical way centrally located, the upper inclined 130

ways being somewhat less in length than the lower way, and that the lower way has a recess in line vertically with the vertical way between the two upper inclined ways, the 5 aforesaid ways being within the base in which the lower end of the post or stile is housed, this construction protecting the roller pin and the ways from the weather. The ends of the upper ways terminate to one 10 side of the center of the stile or post, the terminals being vertical to provide abutments for the bolts, which bolts normally engage the ends of the ways. To relieve the gate against vertical shock, a spring is provided 15 which spring exerts an upward pressure against the lower circular end of the gate stile, and cooperating with this spring there is attached to the upper end of the gate stile a flexible connection that is guided over 20 rollers, the connection being kept under tension by a counter weight which is movable in a hollow post which is maintained by the base. The post carries at its upper end a support for guide rollers and at a suitable 25 distance below the upper end of the gate stile has a band or loop that extends about the gate stile and said band has inwardly projecting studs which are positioned to extend toward opposite sides of the stile for 30 engagement with inclined faces of projections attached to opposite sides of the stile, so that when the stile is lifted the inclined faces or camming surfaces will operate to turn the stile and carry its roller stud to one 35 side of the upper vertical way so the gate will be caused to open to the right or left.

The flexible gate operating connections are guided by rollers on the support 22, and are made fast to eyes through the upper 40 ends of vertical bars 35 and when one of the flexible connections is drawn upon the bar will be raised to retract one of the sliding bolts which permits the roller stud to pass from the upper inclined way to a lower 45 corresponding way, and to limit the upward movement of the gate stile, short flexible connections extend from the band or loop to the eyes of the vertical movable bars which move the bolts to a retracted position against 50 the action of their springs. The upward movement of the bars 35 is restricted by laterally projecting studs which also serve to maintain the inclined projecting faces within the slots formed through the bolts.

55 I claim

1. In a gate operating mechanism, a base consisting of a member having a vertical bore the side wall of which has upper and lower inclined ways and passages connecting the same at their ends and intermediate 60 their ends, the upper way being downwardly inclined from the intermediate passage and the lower way being downwardly inclined from the end passages, a gate supporting member seating in the aforesaid 65

bore and movable vertically therein, said member having a stud for engagement with the inclined ways, and normally positioned in line with the intermediate passage, means for blocking the end passages, means for 70 moving the supporting member upwardly to locate its stud in position to engage the upper way, and means for retracting the blocking means to permit travel of the stud to the lower way. 75

2. In a gate operating mechanism, a base consisting of a member having a vertical bore the side wall of which has upper and lower inclined ways and passages connecting the ways at their ends and intermediate 80 their ends, the upper way being downwardly inclined from the intermediate passage and the lower way being downwardly inclined from the end passages, a gate supporting member seating in the aforesaid bore and movable vertically therein, said member having a stud for engagement with the inclined ways, and normally positioned in line with the intermediate passage, means for blocking the end passages, means for 85 moving the supporting member upwardly to locate its stud in position to engage the upper way, and means for retracting the blocking means, and actuators for the two last-mentioned means located at points 90 remote from the gate supporting member. 95

3. In a gate operating mechanism, a base consisting of a member having a vertical bore the side wall of which has upper and lower inclined ways and passages connecting the ways at their ends and intermediate 100 their ends, the upper way being downwardly inclined from the intermediate passage and the lower way being downwardly inclined from the end passages, a gate supporting member seating in the aforesaid bore and movable vertically therein, said member having a stud for engagement with the inclined ways and normally positioned in line with the intermediate passage, means for blocking the end passages, means for 105 moving the supporting member upwardly to locate its stud in position to engage the upper way, and means for imparting a primary turning movement to the supporting member on the upward movement thereof to position its stud on the upper way, and means for retracting the blocking means. 110

4. In a gate operating mechanism, a base consisting of a member having a vertical bore the side wall of which has upper and lower inclined ways and passages connecting the ways at their ends and intermediate 115 their ends, the upper way being downwardly inclined from the intermediate passage and the lower way being downwardly inclined from the end passages, a gate supporting member seating in the aforesaid bore and movable vertically therein, said member having a stud for engagement with 120

125

- 65

- the inclined ways and normally positioned in line with the intermediate passage, means for blocking the end passages, means for moving the supporting member upwardly
- 5 to locate its stud in position to engage the upper way, inclines on the supporting member, stationary abutments engageable by the inclines when the supporting member is moved upwardly for imparting a turning
- 10 movement to the supporting member to locate its stud on the upper inclined way, and means for retracting the blocking means.
5. In a gate operating mechanism, a base consisting of a member having a vertical bore the side wall of which has upper and lower inclined ways and passages connecting the same at their ends and intermediate their ends, the upper way being downwardly inclined from the intermediate passage and the lower way being downwardly inclined from the end passages, said wall also having a recess intermediate the ends of the lower way and in alinement with the intermediate passage, a gate supporting member seating in the aforesaid bore and
- 15 movable vertically therein, said member having a stud for engagement with the inclined ways, and normally positioned in the aforesaid recess, means for blocking the end passages, means for moving the supporting member upwardly to locate the stud in position to engage the upper way, and means for retracting the blocking means to permit travel of the stud to the lower way.
6. In a gate operating mechanism, a
- 30 socket member having a central bore, a gate post operating in the bore, means carried by the socket member and cooperating with the gate post for moving the gate post to predetermined positions, a gate carried by
- 40 the gate post, a stationary post associated with the socket member and carrying a collar, pins extending inwardly from the collar, camming blocks carried by the gate post, said camming blocks adapted to engage the pins for causing the gate to move in a predetermined direction, and means for rotating the gate.
- 45

FRANK KAHLER.
